UNITED STATES PATENT OFFICE.

SAMUEL E. MCFARLAND, OF LOS ANGELES, CALIFORNIA, ASSIGNOR TO COBB SHOCK-LESS CROSSING CORPORATION, OF NEW YORK, N. Y., A CORPORATION OF NEW YORK.

INTERSECTION-OPERATING SYSTEM.

1,407,209.

Specification of Letters Patent. Patented Feb. 21, 1922.

Application filed February 11, 1918, Serial No. 216,578. Renewed August 22, 1921. Serial No. 494,377.

To all whom it may concern:

Be it known that I, SAMUEL E. MCFARLAND, a citizen of the United States, residing at Los Angeles, in the county of Los Angeles, State of California, have invented new and useful Improvements in Intersection-Operating Systems, of which the following is a specification.

This invention relates to systems and mechanisms for operating railway intersections, including crossing, switches, etc. I shall explain the system and mechanism which embody my invention as applied to a crossing; but it will be understood that my invention may be applied to any kind of intersection or junction.

In most situations at crossings or junctions there is more, and in a great many cases a great deal more, traffic on one of the intersecting tracks than upon the other. For this reason, and for other reasons unnecessary to here relate, it is desirable to provide that an intersection mechanism shall be normally in position to pass trains on the most traveled track and be only set in position for trains on the least traveled track when a train approaches on that track. It is an object of this invention to provide a simple mechanism for such a purpose as herein outlined.

It is also within the objects of the invention to provide a mechanism which is controlled for positive actuation entirely by a car or train upon one track, although it may be controlled by a car or train on the other intersecting track to prevent actuation when that car or train is crossing the intersection; to provide a system whereby the intersection mechanism will be set as a train approaches upon one track, and wherein the mechanism will remain set in that position until the last car of a train is across the intersection; to provide that a train leaving the intersection cannot reverse the intersection mechanism immediately ahead

of a following car or train which is just about to cross the intersection; to provide a system in which proper actuation and operation of the parts will take place regardless of the direction in which a car or train passes on any track over the intersection; to provide a system in which a car or train

when crossing the intersection cannot lose control of the mechanism; and, further, to provide for return of the mechanism if it has been accidentally set in abnormal position and not returned to normal. 55

It is also an object, in any kind of an intersection system (regardless of whether the intersection mechanism is controlled by the cars or trains on one or all of the tracks) 60 to provide a system by which a car or train when once it has set the mechanism for its passage across the intersection (or is holding the mechanism against being set against its passage across the intersection) 65 will hold control of the mechanism during all the time of its passage across the intersection and until it is clear of the intersection. In the following description I set forth the application of this feature of my invention to the positive control and operation of the crossing mechanism by a car or train upon one track, and also to the negative control of the crossing mechanism by a car or train upon the other track. 75

It is further a general object of this invention to provide a simple, efficient, and easily and infallibly operated means for actuating the intersection mechanism itself. And all these main objects, and others, will be readily understood from the following detailed specification of a preferred form of my invention, as applied to a crossing mechanism. Such a crossing mechanism as herein indicated is shown and described in 80 United States Patents of Edward S. Cobb, No. 1,074,082, Sept. 23d, 1913; No. 1,257,- 85 279, Feb. 19th, 1918; and No. 1,257,280, Feb. 19th, 1918; and in others not necessary to mention herein. I make no claim to such 90 mechanisms.

It is not only an object of this mechanism to provide a suitable control system, but also to provide a combination by which that control system may be efficiently combined with 95 the means which directly actuates the intersection mechanism itself.

In the accompanying drawings I illustrate a preferred form of mechanism and system. In these drawings Fig. 1 is a plan, 100 with parts in section, showing the application of my invention to a typical crossing

mechanism; Fig. 2 is a section illustrating the construction of a crossing mechanism to which the invention may be applied, said section being taken on line 2—2 of Fig. 1; 5 Fig. 3 is a similar section taken on line 3—3 of Fig. 1; Fig. 4 is an enlarged detail section of the controlling mechanism which controls the actuation of the mechanism which in turn operates the crossing mechanisms; Fig. 5 is a view showing the 10 construction of a preferred form of controlling relay; Fig. 6 is a section taken as indicated by line 6—6 on Fig. 5 and showing the relay in its normal position; Fig. 7 is a similar section showing the relay in a typical 15 actuated position; and Fig. 8 is a diagram showing the electrical connections of the system.

In order to illustrate my invention I show 20 its application to an intersection where a single track T^1 crosses two tracks T^2 ; but it will be readily understood how my mechanism may be applied to any number of tracks crossing any number of other tracks.

25 At each individual track intersection or crossing there is an intersection mechanism I whose function it is to make a continuous smooth rail passage across the intersection upon either track. Each intersection has 30 two pairs of movable rail parts R^1 and R^2 ; and it is a function of this mechanism to raise and lower these pairs of rail parts R^1 and R^2 so as to make either pair flush with the track rails on which they form continuations. 35 This operation is accomplished by the back and forth rotation of shafts 10 within the intersection mechanisms I, two in each mechanism. Sprocket chains 11 may connect the two shafts of each mechanism, so 40 as to cause the shafts to operate synchronously; the cams 12 and 13 on these shafts cause the rails parts, R^1 and R^2 to be raised and lowered as the shafts are rotated back and forth. Each of these intersection mechanisms may typically comprise the following 45 described parts.

In Figs. 2 and 3 the numeral 9 designates the box base in which an intersection or crossing mechanism is mounted. The two 50 shafts 10 are mounted in suitable bearings 100, and carry the cams 12 and 13, which operate under rail portions R^1 and R^2 , respectively. In the drawings the rail portions R^2 are shown in upper position and rail portions 55 R^1 in lower position. It will readily be seen by inspection of Figs. 2 and 3 that the cams 12 and 13 are so shaped that, upon movement of the chains 11 in the direction indicated, the cams will act to raise rail portions R^1 and lower rail portions R^2 . When 60 these rail portions are in their uppermost position their upper tread surfaces are flush with and form continuations of the upper tread surfaces of the respective rails of 65 the tracks T^1 and T^2 ; the lowered rail por-

tions in each case being far enough down to clear the flanges of wheels which pass on the rail portions which are raised.

The two intersection mechanisms I may be identical; and may be arranged so that, 70 when they are in the positions shown in the drawings, all the rail parts R^1 are lowered, while all the rails parts R^2 are raised. That is, the rail passages of tracks T^2 are continuous across the intersection. Rotation of 75 the shafts 10, and movement of the chains 11, in the directions indicated by the arrows in the various views, will cause the movement of the parts so as to lower the rail parts R^2 and raise the rail parts R^1 . Movement of the shafts, and simultaneous movement thereof, for both the intersections I, 80 may be efficiently caused by a fluid pressure mechanism comprising a cylinder 20 with a piston 21 mounted upon a piston rod 22 85 which projects through both cylinder heads 23 and is attached at its opposite ends at 24 to the two chains 11. With the piston 21 in the position indicated, the tracks T^2 are clear. 90

It is a function of the control system and control mechanism to cause the intersection mechanisms to be set to make the track T^1 clear when a train approaches the intersection in either direction on the track T^1 , 95 and to hold the intersection mechanisms in that condition during all the time that the car or train is passing across the intersection, not losing control of the mechanism and not allowing the intersection mechanisms to resume their normal positions until the car or train is entirely across the intersection and then to cause the infallible return of the intersection mechanisms to their normal position in which tracks T^2 are 105 clear. In order to accomplish these results, the positive control if effected entirely by a car upon the track T^1 ; cars or trains approaching upon the tracks T^2 do not cause the operation of the crossing mechanism. 110

(However, as hereinafter explained, cars or trains on track T^2 can, under certain circumstances, prevent operation by a car or train on track T^1). I provide in the track T^1 two insulated rail sections 30 and 31 situated on opposite sides of the intersection. 115 For the purposes of operating the system, a battery may be used, as illustrated at B; and an intermediate plate of the battery may be connected by wire 32, 32^a to any one of the 120 grounded rails of the track. From the insulated rail section 30 there extends a wire 33, connecting to one side of a solenoid 34, the other side of this solenoid being connected by wire 35, 35^a to one side of battery B. 125 From wire 35 a branch wire 35^a leads to one side of another solenoid 34^a, the other side of this solenoid being connected by wire 33^a to the insulated rail section 31.

These solenoids 34 and 34^a each are adapt- 130

ed to pull a core 34^b and 34^c, respectively, upwardly; and the upward movement of each core 34^b and 34^c moves an arm 36 or 36^a upwardly. Arms 36 and 36^a are pivoted at 37 and they each carry a contact arm 38 and 38^a respectively, adapted to engage with either of stationary contacts 39 or 40, and 39^a or 40^a. In the normal position of the parts, which position is shown in the drawings, the arms 38 and 38^a engage the contacts 39 and 39^a, respectively. (Description of the arms 158 and 158^a is deferred to a later part of this specification.) When the arms 36 and 36^a are raised, the contact arms 38 and 38^a engage contacts 40 and 40^a, respectively. The ends of arms 36 and 36^a are shaped as is shown in Figs. 5, 6 and 7, with a convex outside surface. Immediately over the ends of these arms there hangs a catch or hook member 45 which has two dependent prongs 46; and in the upper part of each prong there is a hook 47 in which the arm 36 or 36^a will catch when it is raised. The arrangement is such that, if either of the arms is raised, the arm will press the member 45 over and will pass above the hook 47 and then, upon being dropped, will catch in the hook 47. Member 45 is pivoted at 48 so that it swings easily. In Fig. 7 I show the arm 36 hooked up by the member 45. The arm 36 hanging in the member 45 causes that member 45 to hang out of its normal vertical position to such an extent that, when the arm 36^a is subsequently raised, then this arm will pass inside the prong 46. This arm 36^a passing inside the prong 46 causes the member 45 to be thrown further from its normal vertical position, far enough to release the arm 36 from the hook 47; and thus arm 36 will be dropped by virtue of the upward movement of arm 36^a, without arm 36^a being itself caught by hook member 45. Thus, the operation of this relay mechanism will be seen to be as follows: Whenever either of the solenoids is energized, the corresponding relay arm and switch will be moved to its abnormal position where it will be caught and held until the other relay arm and switch are moved by the energization of the other solenoid. The second moved arm is not held up by the hook member 45 but will be itself dropped whenever its solenoid is de-energized. This operation takes place regardless of which arm and switch is actuated first.

The two contacts 40 and 40^a are connected together by wire 50, while contact 39^a is connected to switch arm 38 by a wire 51. A wire 52^a leads from wire 50 through a circuit hereinafter to be explained, to a wire 52^b which leads to one side of a solenoid 53 while a wire 54 leads from contact 39 to one side of a solenoid 55. (For the purpose of the immediately following explanation the circuit through wires 52^a and 52^b may be

considered as if closed, which it normally is and is only opened under certain circumstances hereinafter set forth). These two solenoids 53 and 55 are those which cause the controlling actions which control the crossing operating mechanism. Of course, it will be understood that, as far as this invention is concerned, the mechanism which actually and directly causes the operations of the crossing may be of any desired character; and upon the character of this mechanism will depend the character of the controlling mechanism which is operated by the solenoids 53 and 55. In the present case, the operating mechanism is shown to be of the fluid pressure variety, and therefore the solenoids 53 and 55 actuate a valve device adapted to control admission and exhaust of fluid pressure to and from the operating mechanism.

The two cores 60 of the solenoids 53 and 55 (Fig. 4) are connected together and are pivotally connected at 61 with a pivotal arm 62 to which the valve rod 63 is directly connected. Valve rod 63 connects to slide valve 64 which may be of any suitable type sliding in valve box 65. This valve box has an exhaust port 66 and two cylinder ports 67 and 68. Port 67 is connected by pipe 69 with the end of the cylinder 20 at which the piston 21 normally stands; while port 68 is connected by pipe 70 with the other end of the cylinder. Valve 64, in its normal central position, connects both the ports 67 and 68 to exhaust port 66. If the valve 64 is moved in the direction indicated by the arrow in the drawings, it will connect port 67 with the fluid pressure space outside the valve, allowing fluid pressure to move into the port 67, and thence through the pipe 69 into the end of the cylinder 20, causing the movement of piston 21 in the direction indicated in Fig. 1, which causes the operation of the crossing mechanisms to lower the rails R² and raise the rails R¹. When the piston 21 has moved through its complete stroke, a collar 75 on the piston rod will strike the end 76^a of a rod 76 and cause that rod to move in the direction indicated in Figs. 1 and 4. The rod 76 carries a contact 77 which is normally in engagement with two stationary contacts 78 and 79. When the rod 76 is moved in the direction indicated, the contact 77 is moved so that it then makes engagement with stationary contacts 79 and 80. This shifting of the contact plate 77 causes, as will hereinafter be described, the throwing of the valve 64 back to its normal position, causing the fluid pressure to be cut off from the cylinder 20 and causing the fluid pressure in the cylinder to be exhausted therefrom.

Pivoted arm 62 carries a contact arm 85 normally standing between the two adjacent ends of stationary contacts 86 and 87

and adapted to be carried onto contact 86 when the arm 62 is moved in the direction hereinbefore described by the energization of solenoid 53, and adapted to be carried 5 onto the contact 87 by movement in the opposite direction. A wire 90 connects the other side of battery B with contact 79, while contacts 78 and 80 are connected by wires 91 and 92 to the solenoids 53 and 55, 10 respectively. Contact 86 is connected by wire 93 with the wire 54 which leads to solenoid 55, and contact 87 is connected by wire 94 with wire 52^b which leads to solenoid 53.

15 Suppose now a train or car to be approaching on track T¹ in the direction indicated by the arrow in Fig. 8. As soon as a truck wheel has entered upon rail portion 30, a circuit is established between that 20 portion and the opposite grounded rail, establishing a circuit described as follows: from battery B through wires 35^c, 35 to solenoid 34 and thence through wire 33 to rail 30, across to the grounded rail and 25 through wires 32^a, 32 back to the battery. Solenoid 34 being energized, the arm 36 is raised, throwing switch arm 38 across into engagement with contact 40. As soon as this action takes place, a circuit is es- 30 tablished as follows: from battery B through wires 35^c, 35, 35^a and wires 35^b and 35^d (which connect wire 35^a to switch arm 38^a) thence through switch arm 38^a, contact 39^a, wire 51, switch arm 38, contact 40, wire 50, wires 52^a, switch arm 138, contact 139, wire 140, switch arm 138^a, contact 139^a, wire 52^b, solenoid 53, wire 91, contacts 78, 77 and 79 and wire 90, back to the battery B. Solenoid 53 being thus en- 40 ergized, it moves its core 60 and the pivoted arm 62 and all connected parts in the direction indicated in the drawings; and by so doing it draws the valve 64 to the position hereinbefore described to supply fluid 45 pressure to move piston 21 in the direction indicated, and it also by the same action throws switch arm 85 around onto contact 86. Now, the arm 36 having been moved upwardly, it is held up by the hook member 45, as hereinbefore explained, so that, once the relay arm 36 has been moved upwardly, and this upward movement is almost instantaneous, then subsequent operations of the mechanism are carried 50 through regardless of whether there is a continuing connection between the rail part 30 and the opposite grounded rail. In other words, for this part of the operation, it is not necessary that rail 30 be very long.

55 Piston 21 moves in the direction indicated by the arrow in Fig. 1, and toward the end of its movement the collar 75 engages the ends 76^a of rod 76, and further movement of the piston then causes the 60 movement of contact 77 over onto contact 80. As soon as contact 77 touches contact 80, a circuit is then established for the other solenoid 55. That circuit is as follows: from battery B, through wire 35^c, wire 89, (which leads from wire 35^c, to contact arm 70 85) arm 85, contact 86, (with which the arm 85 is then in engagement), wire 93, solenoid 55, wire 92, contacts 80, 77 and 79, and wire 90, back to the battery B. The energization of solenoid 55 causes the movement of the solenoid cores and switch arm 85 in a direction opposite to that indicated; and this movement will continue until the arm 85 is drawn off the contact 86, when the said circuit will be broken and the parts 80 of the control mechanism will all then be stopped in their normal medial positions. The piston 21 is now in its position at the end of cylinder 20 opposite to that in which it is shown in Fig. 1, and the crossing mechanisms are in position opposite to that shown in the drawings, and the relay arm 36 is still hooked up. As long as this relay arm is hooked up, (or as long as either one of the relay arms is hooked up), 90 the crossing operating mechanisms and the crossings will not return to the normal positions but will remain in their abnormal positions until both the relay arms 36 and 36^a are lowered. The only manner in which 95 relay arm 36 can be lowered is to release it by raising the arm 36^a.

100 The relative position of insulated section 30 is such that when a car or train approaches or runs on to that section, and causes the operations which have been described, those operations will take place and be completed before the car or train reaches the intersection. When the car or train reaches the intersection it passes over on a 105 smooth, continuous and unbroken track, and then its forward wheels pass onto the insulated rail section 31. A circuit is then set up from battery B through wires 35^c and 35, wire 35^a, solenoid 34^a, wire 33^a, rail section 31, across to the opposite grounded rail, and thence through wires 32^a and 32 back to the battery. Relay arm 36^a is thus raised, and the raising of this arm causes 110 the release of relay arm 36, and the arm 36 will then be dropped if there are no wheels 115 yet upon the insulated rail portion 30. Arm 36 will be unhooked immediately when arm 36^a is raised, and it will then be immediately dropped, or will be subsequently dropped 120 when the last wheel has passed off insulated rail portion 30. But arm 36^a will remain up in any case, until the last wheel has passed off insulated rail portion 31. This is so because the insulated rail portion 31 125 (and also portion 30—because this whole system is designed to operate regardless of the direction in which a car or train approaches on the track T¹) is long enough that, after the first wheel has run upon it, 130

there is never then a time at which there is not at least one wheel on the rail 31 until the last wheel leaves it. Thus, during all the time there is any wheel on rail portion 31, the relay arm 36^a will be held up by the action of the solenoid 34^a. Further, it will be noted that, from the time the first wheel runs upon the rail portion 30, until the time the last wheel leaves rail portion 31, one or the other, or both, of the relay arms 36 and 36^a are held up. It will be seen from what is explained following, that when either one or both of these arms are up, the intersection mechanisms will be thrown to and held in their abnormal positions. I have explained how the intersection mechanisms are thrown to their abnormal positions when the arm 36 is raised, due to the establishment of an electrical circuit through the solenoid 53; and I have explained how, by the action of the piston, the circuit through the solenoid 53 is broken and a circuit established through the solenoid 55 to energize that solenoid and to thus carry the solenoid mechanism (that is, the controlling mechanism) back to its normal medium position. Now, as is hereinafter explained, in order for the controlling mechanism to so actuate as to cause the intersection mechanisms to move back to their normal positions, it is necessary that both the relay arms 36 and 36^a be down. When a wheel has entered on the rail part 31, and the relay arm 36^a has been thereby raised, the contact arm 38^a has left off engagement with contact 39^a before the contact arm 38 can move back into its normal engagement with contact 39. Contact arm 36 moves back to its normal position, either when it is unhooked or whenever the last wheel moves off the insulated rail section 30; and contact arm 38^a moves back to its normal position when the last wheel moves off insulated rail section 31. Immediately both these contact arms 38 and 38^a have reached their normal positions, then a circuit is established as follows:

From battery B through wires 35^c and 35, wire 35^a, wires 35^b and 35^d, contact arm 38^a, contact 39^a, wire 51 contact arm 38, contact 39, wire 54, solenoid 55, wire 92, contacts 80, 77 and 79, and wire 90, back to the battery B. Energization of the solenoid 55 in this manner (without depending upon the making of the contact through arm 85 and contact 86) causes the solenoid core to be moved in a direction opposite to that indicated, causing the valve 65 to be moved to a position opposite to that hereinbefore described, allowing fluid pressure to pass through pipe 70 to the end of the cylinder at which the piston 21 then stands, to move the piston back to the position shown in Fig. 1. When the piston approaches this position shown in Fig. 1, the collar 75 on piston rod 22 strikes end 76^b of rod 76 and moves that rod back to its normal position where the contact 77 again engages the two contacts 78 and 79. As soon as the contact 77 leaves contact 80, the circuit to solenoid 55 is broken; and as soon as contact 77 touches contact 78, a circuit is established through the solenoid 53 as follows: from battery B through wires 35^c and 89, arm 85, contact 87, wire 94, wire 52^b, solenoid 53, wire 91, contacts 78, 77 and 79, and thence through wire 90 back to battery B. Energization of solenoid 53 causes the movement of the control mechanism back to its normal medial position, where the circuit through the solenoid 53 is broken by the arm 85 leaving engagement with contact 87. The parts are then all back in their normal positions; both the relay arms are in their normal lower positions, the control mechanism is in its normal medial position, the contact 77 is in its normal position engaging contacts 78 and 79, and the intersection operating mechanism and the intersection mechanisms themselves are all in normal position making a clear passage on track T².

I will now explain how this mechanism acts to the same effect as hereinbefore described, when a car or train approaches on track T¹ in the direction opposite to that indicated in Fig. 8. Such a car or train will pass first onto rail section 31 and it will thereby make connection between this rail section and the opposite grounded rail, and thereby establish the same circuit as hereinbefore described, through the relay solenoid 34^a, raising the relay arm 36^a, which is then hooked up. Relay arm 38^a is thus thrown over against contact 40^a. A circuit is thus established through the solenoid 53 in the same manner as it was before established by action of the relay arm 36, because the two contacts 40 and 40^a are connected together by the wire 50. Consequently, the solenoid 53 is energized to move the core 60, and to cause the actuations of the various parts in exactly the same manner as hereinbefore described. The train having passed on over the intersection and run onto rail portion 30, relay solenoid 34 is thereby energized in the same manner hereinbefore explained, causing relay arm 36 to move upwardly, and throwing relay switch arm 38 over against the contact 40 and away from contact 39. The upward movement of arm 36 releases the arm 36^a which theretofore had been hooked up, allowing the arm 36^a to drop (providing relay solenoid 34^a is not still energized; and allowing it to drop in any event after that energization has ceased). Relay arm 36 will remain in its raised position until the last wheel leaves rail portion 30. During this time, and at all times while switch arm 38 is out of engagement with contact 39, no current can flow through the

circuit hereinafter described for the solenoid 55. It will be remembered that in the former situation, the break between arm 38^a and contact 39^a prevented the flow of current to solenoid 55. In the present situation, because contact 39^a and arm 38 are in series in this circuit, the circuit is similarly broken between arm 38 and contact 39. Consequently the solenoid 55 cannot be energized 10 until the relay arm 36 drops to its normal position, which it will not do until the last wheel has passed off rail section 30. When the last wheel does pass off rail section 30, then arm 36 drops to its normal position and 15 the circuit through solenoid 55 (the same as hereinbefore described) is again made, and solenoid 55 acts to throw the parts in the direction opposite to that indicated by the arrows, causing reverse operation of the 20 crossing operating mechanism and causing the crossing operating mechanism and the crossing mechanisms themselves to come back to normal position. At the end of this operation of the crossing mechanisms the 25 control mechanism is moved back to its normal medial position, as hereinbefore explained.

It will now be understood how the system herein described acts to cause the same sequence of intersection operations regardless 30 of the direction in which a car or train passes over the intersection. The control mechanism has three positions—a normal position in which it holds the operating 35 mechanism at rest, one position in which it causes operation in one direction, and another position in which it causes operation in the opposite direction. The control mechanism and the operating mechanism are 40 equipped with means to bring the control mechanism to its normal medial position of rest whenever either of the two operations is completed.

The function of the controlling system is 45 to cause the same sequence of operation of the control mechanism regardless of the direction in which a car or train passes the intersection. This is accomplished by having in the control system two relays, one 50 adapted to be actuated by a train at one side of the intersection, the other adapted to be actuated by a car at the other side of the intersection; the actuation of either of which relays causes the same operation of the 55 control mechanism, and which relays it is necessary both to be unactuated or de-energized in order to cause a reverse operation of the control mechanism. The feature of hanging up one of the relays until the other 60 one is actuated makes it impossible, after either one of the relays has been actuated, to at any time have both relays back in their normal unactuated positions until the other relay has been actuated and finally de-energized. The control rails being longer than

the longest distance between wheels of a car or train, makes it impossible to de-energize a relay at any time until the last wheel passes off the rail. The hanging up of an initially actuated relay provides that if a car shorter 70 than the distance between the adjacent ends of rail sections 30 and 31 passes across the intersection, it will not, because it passes off one rail section before it passes on to the other, allow the crossing mechanisms to be 75 then reset in their original normal position.

The foregoing description has been made without describing the control which a car or train on track T² may have on the crossing mechanisms. This will now be explained. 80 It will have been noted that in order to throw the crossing mechanism from its normal position it is necessary that current shall flow through wires 52^a and 52^b to the solenoid 53. Now, in the foregoing description, the circuits have been described as if wires 52^a and 52^b form a continuous closed part of the circuit. This is true at all normal times; but if a car or train should approach on track T², then the circuit is 85 broken at wire 52 in a manner now to be explained.

I provide on tracks T² insulated rail portions 130 and 131. The portions 131 are connected together by wire 132 and are together connected to solenoid 134 by a wire 133. Rail portions 130 are connected together by wires 135 and 135^a and are connected to solenoid 134^a by wires 136, 136^a. The circuit for solenoid 134 leads from battery B through wire 35^c, wire 145 and wire 146 to solenoid 134 and thence through wires 133 and 132 to the insulated rail sections 131 and thence across to a grounded rail and back through wire 32^c, 32 to the 100 battery. The circuit for solenoid 134^a is substantially the same except that it involves the wires 136, 136^a and 135, 135^a and the insulated rail sections 130. These solenoids 134 and 134^a form part of a relay 110 mechanism substantially similar to that hereinbefore described except that in this relay mechanism there is a single contact arm 138 or 138^a which engages, when the relay is de-energized, with a single contact 139 115 or 139^a. When both these relay mechanisms are de-energized then the circuit from wire 52^a to wire 52^b is complete and unbroken; through wire 52^a, arm 138, contact 139, wire 140, arm 138^a, contact 139^a, and wire 52^b. 120 If either one of the relay solenoids 134 or 134^a is energized, the circuit is broken. If a car approaches on either track T², it will energize first the solenoid 134, raising the relay arm 136^b and causing it to be hooked up in 125 the manner hereinbefore explained. The circuit will thus remain open at 138—139 while that car passes across the intersection. When that car has passed over onto rail portion 131 it energizes the other sole- 130

noid 134^a, raising relay arm 136^c, breaking the circuit at 138^a—139^a, and allowing the relay arm 136^b to drop. When this car leaves rail portion 131, then the circuit will be again established at 138—139^a. Thus it will be seen that any car or train passing across the intersection on track T² will cause a break in the circuit of wire 52 at all times while it is passing over the intersection. A break in the wire 52 makes it impossible for any car subsequently approaching on track T¹ to energize the solenoid 53 and to thus operate the crossing. Consequently any car or train approaching or traversing the crossing on track T² protects itself against the crossing being operated while it is passing. However, if the car on track T¹ has arrived first and set the mechanism in operation, the arrival of a car on track T² will not stop that operation; because after solenoid 53 is once energized, the crossing actuating mechanism goes through its operation automatically to the end. And, further, the breaking of the circuit in wire 52 does not at all hinder the return movement of the system and mechanisms to put the crossing back in its normal position to pass a car on track T². If a car is standing on track T² close to the crossing while a car is crossing on the other track, as soon as the second mentioned car moves off the insulated rail section after passing the crossing, then the mechanism automatically returns to position to pass the waiting car.

In a system of this general character it is desirable that provision be made for throwing the crossing mechanisms back to their normal positions if they should be accidentally thrown from their normal positions. If, for any reason or cause, one of the rails 30 or 31 should be grounded without a subsequent grounding of the other one of these rails, the crossing mechanisms will thereby have been moved from their normal positions and will be left in their abnormal positions. Suppose, for instance, that a metal wagon tire should ground one of the rails for a short time; or suppose that a car should move up to the crossing, grounding one of the rails, and then back away from the crossing without going on over to the other rail. In such a case, the mechanism would be operated to its abnormal position and left in that position. To overcome such a difficulty as this, I provide an automatic means which will, after the lapse of a certain time period, return the crossing to its normal position. Said time period begins to elapse after the grounding of the rail has ceased; so that if a car stands for an indefinite time upon one insulated rail, the crossing mechanism will not be thrown back to normal position until the car leaves that rail, and then only after a predetermined time has elapsed.

In order to effect this emergency opera-

tion, I equip the relay mechanism with another pair of contact arms 158 and 158^a. When the relay is de-energized these arms engage the contacts 159 and 159^a and when the respective solenoids are energized these arms engage respectively the contacts 170 and 170^a. At 175 I provide a time period mechanism in the form of a thermostat which may comprise superimposed bars of different metals 176 surrounded by a resistance winding 177. Passage of current through the resistance winding heats the bars and causes them to move in the direction indicated by the arrow, raising a contact plate 178 against two contacts 179 and 180. One end of the resistance winding is connected by wire 181 to wire 32 leading to the battery B; and contact plate 178 is also connected by wire 182 to the wire 181. Contact 179 is connected by wire 183 with wire 33^a which connects insulated rail section 31 with solenoid 34^a; while contact 180 is connected by wire 184 with wire 33 which connects insulated rail section 30 with solenoid 34. It will thus be seen that the switch formed at 180—178 is in parallel, with reference to solenoid 34, with the gap between insulated rail section 30 and the grounded rail on the other side of the track. And the switch formed at 178—179 bears the same relation to the gap between insulated rail section 31 and the ground. Consequently, when the thermostat has raised contact 178, it will be seen that both solenoids 34 and 34^a will be energized in exactly the same manner as they would be energized by the grounding of rails 30 and 31.

The other end of the resistance winding 177 is connected by wires 185, 186 and 187 to the contacts 170 and 170^a. The two contacts 159 and 159^a are connected together by wire 188, and are both connected to the battery B through a wire 189 which connects with wire 35^b which connects back through wires 35^a, 35 and 35^c to the battery. And the two switch arms 158 and 158^a are connected together by a wire 190. Suppose now that rail 30 is temporarily grounded, causing relay arm 36 to move upwardly and be hooked in its upper position and causing the crossing mechanisms to be thrown to their abnormal positions, in the manner hereinbefore described. Current immediately flows from battery B through wires 35^c, 35, 35^a, 35^b, 189, 188, contact 159^a, arm 158^a, wire 190, arm 158, contact 170, wire 186, wire 185, thermostat winding 177, and wires 181 and 32 back to the battery. Now, if the rail 30 is still grounded, the current will be largely diverted from the circuit just described, the current then flowing from wire 35 through solenoid 34, wire 33, rail 31, ground and wire 32 back to the battery. As soon as the grounding of rail 30 has ceased, then thermostat winding is sup-

plied with full current, and the thermostat begins to act. After a certain time period the contact 178 will engage contacts 179 and 180. The immediate result of this is to again energize not only the solenoid 34 but also solenoid 34^a. Energization of solenoid 34^a causes arm 36^a to move upwardly, releasing the other arm and allowing both arms to drop simultaneously. This they 10 will do because, as the arm 36^a moves upwardly, it draws the hook member 45 far enough around to the right in Fig. 7 to disengage arm 36 so that, upon a subsequent simultaneous release of both arms, both 15 arms will fall freely. It will be noted that in order to supply the thermostat with current, one of the switch arms 158 or 158^a must be in its normal position, while the other is in its abnormal position. If both 20 of them are in normal position, or both in abnormal position, then the thermostat is not supplied with current. This is true because the current which is supplied to the thermostat must flow either through contact 25 170 or 170^a. In order to get to either of these contacts it must flow through either the arm 158 or the arm 158^a, which are connected together by wire 190. Battery current is fed to contacts 159 and 159^a. Consequently, in order to get current to the thermostat one of the arms must be in normal 30 position engaging a contact 159 or 159^a while the other must be in abnormal position engaging the contact 170 or 170^a. Consequently, when both solenoids 34 and 34^a are energized by the action of the thermostat, then the current through the thermostat is broken, and as soon as the thermostat has cooled off sufficiently to break the 40 circuit at 178 to 179 and 178 to 180, then the relay arms 36 and 36^a will be dropped. When both these arms are dropped, then the crossing mechanisms will be moved back to their normal positions in the manner 45 which has been before explained.

It will be seen that a similar thermostat controlled operation will take place if the rail 31 is grounded, in the manner above explained for the grounding of rail 30. In 50 fact it will be seen that this part of the system, as well as all other parts, works and operates in identic fashion regardless of which rail is grounded first.

The thermostatic control may of course 55 be applied to the relay mechanism connected with track T² as well as to that connected with track T¹. The same conditions prevail in either case. In each case the approaching car actuates a control means that 60 performs a certain function with relation to the mechanism or system and that function persists until that car passes on over the intersection and actuates another means that terminates the function—terminates it, as

herein described, by releasing the first actuated control means. If, for any reason, one control means is actuated and the other not subsequently actuated, then it becomes the function of the time period mechanism to cause the second actuation. Thus, for instance, if for any reason a rail 130 should have been accidentally grounded, causing the circuit of wire 52 to be broken at 138^a—139^a, that circuit would remain broken indefinitely and the actuating means 70 remain powerless to act, unless a rail 131 be subsequently grounded. This the time period mechanism will do if it is connected up with the relays for track T² in the same manner as hereinbefore described for the 80 relays for track T¹. I illustrate thermostat 275 having winding 277, contact plate 278, and contacts 279 and 280. Wire 281 connects to wire 32^a and to one side of the winding 277 and also to plate 278. A wire 85 283 connects one contact 279 with the wire 136^a which leads to solenoid 134^a. A wire 284 connects to the other contact 280 and to the wire 133 which connects to the solenoid 134. The other side of the winding 90 277 is connected to wire 285, and by means of wires 286 and 287 to contacts 270 and 270^a, respectively. These two contacts are adapted to be engaged by the contact arms 258 and 258^a, respectively, when the relay 95 solenoids are energized. When the relay solenoids are not energized, these arms engage contacts 259 and 259^a, respectively. Contacts 259 and 259^a are connected together by wires 288, 288^a; and wire 288 is connected by wire 100 289 to wire 89 which leads back to wire 35^c and thence to the battery B. The two arms 258 and 258^a are connected together by wire 290.

It will be seen, without the necessity of 105 following out the several circuits, that the thermostatic mechanism in this situation operates with regard to the relay, the same as the thermostatic mechanism of track T¹ operates with regard to its relay.

Having described my invention, I claim:

1. In combination with two intersecting tracks and an intersection mechanism adapted to make either track continuous at the intersection, operating mechanism for 115 the intersection mechanism, and a control system for the operating mechanism, said control system embodying two controlling means having each a normal position causing the operating mechanism to assume a 120 certain normal position, said controlling means being actuatable one by a car or train at one side of the intersection and the other by a car or train at another side of the intersection, and either of said controlling 125 means when so actuated causing operation of the operating mechanism from its normal position, and means to hold either of

said controlling means in its actuated position, said means being releasable by the other controlling means when actuated.

2. In combination with two intersecting tracks and an intersection mechanism adapted to make either track continuous at the intersection, operating mechanism for the intersection mechanism, and a control mechanism having two actuating positions in 5 one of which it causes the movement of the operating mechanism to a certain normal position and in the other of which it causes the movement of the operating mechanism away from its normal position, and 10 a controlling system embodying two controlling means each having a normal position in which they together cause actuation of the controlling mechanism to its first mentioned actuating position, one of said 15 controlling means being actuatable by a car or train at one side of the intersection and the other being actuatable by a car or train at another side of the intersection, and either of said means being capable in its 20 actuated position to cause movement of the controlling mechanism to its second mentioned position, and means holding either of said controlling means in its actuated position, said holding means being releasable by the other controlling means when actuated.

3. In combination with two intersecting tracks and an intersection mechanism adapted to make either track continuous at the intersection, operating mechanism for the intersection mechanism, a controlling mechanism embodying a means controlling supply of energy to the intersection operating mechanism, said means having two actuating positions, one in which it supplies energy to move the operating mechanism away from a normal position, and the other in which it supplies energy to move the operating mechanism back to its normal 45 position, an electro-magnet to move said means to its first mentioned position, and another electro-magnet to move said means to its second mentioned position; and a control system embodying a pair of relays, 50 electrical circuits including the windings of said relays and including also means in association with a track at points on opposite sides of the intersection whereby a car or train may close the circuit to one or 55 the other of said relays and cause movement of such relay from a normal to an actuated position; an electrical circuit including the first mentioned electro-magnet and adapted to be closed by the actuation 60 of either of said relays, and an electrical circuit including the second mentioned magnet and adapted to be closed by said relays when both of them are in normal position.

4. In combination with two intersecting 65 tracks and an intersection mechanism

adapted to make either track continuous at the intersection, operating mechanism for the intersection mechanism, a controlling mechanism embodying a means controlling supply of energy to the intersection operating mechanism, said means having two actuating positions, one in which it supplies energy to move the operating mechanism away from a normal position, and the other in which it supplies energy to move the 70 operating mechanism back to its normal position; an electro-magnet to move said means to its first mentioned position, and another electro-magnet to move said means to its second mentioned position; and a 75 control system embodying a pair of relays, electrical circuits including the windings of said relays and including also means in association with the track at points on opposite sides of the intersection whereby a 80 car or train may close the circuit to one or the other of said relays and cause movement of such relay from a normal to an actuated position; an electrical circuit including the first mentioned electro-magnet 85 and adapted to be closed by said relays when both of them are in normal position; and means for holding either relay in its actuated position, said means being releasable by the other relay when actuated. 90

5. In combination with two intersecting tracks and an intersection mechanism adapted to make either track continuous at the intersection, means for causing the operation of said mechanism and for causing it normally to assume a position in which it makes one of said tracks continuous, control means actuatable by a car or train on the other track to move the mechanism to its position to make that other track continuous, and means controllable by a car or train on the first mentioned track to prevent said last mentioned movement of the mechanism. 100

6. In combination with two intersecting tracks and an intersection mechanism adapted to make either track continuous at the intersection, means for causing the operation of said mechanism and for causing it normally to assume a position in which it makes 105 one of said tracks continuous, control means actuatable by a car or train on the other track to move the mechanism to its position to make that other track continuous, and means controllable by a car or train on the first mentioned track to prevent said last mentioned movement of the mechanism, said last mentioned means having no effect upon the operation of the mechanism assuming 115 its normal position. 120

7. In combination with two intersecting tracks and an intersection mechanism adapted to make either track continuous at the intersection, a controlling system for the mechanism embodying a pair of controlling 130

means actuatable by cars or trains on opposite sides of the intersection, either of said controlling means when actuated controlling the intersection, and interacting means between the controlling means holding either of them in its actuated position and releasable by the other when actuated.

8. In combination with two intersecting tracks and an intersection mechanism adapted to make either track continuous at the intersection, a controlling system for the mechanism embodying a pair of controlling means actuatable by cars or trains on opposite sides of the intersection, either of said controlling means when actuated controlling the intersection, interacting means between the controlling means holding either of them in its actuated position and releasable by the other when actuated, and time period mechanism operable at times causing the actuation of the other controlling means after the one first mentioned controlling means has been actuated.

9. In a system of the character described, two intersecting tracks and an intersection mechanism adapted to make either track continuous at the intersection, a controlling system for the mechanism embodying a pair of controlling means actuatable by cars or trains on opposite sides of the intersection, said controlling means when both in unactuated position causing the mechanism to assume a certain normal position making one of the tracks continuous, either of said controlling means when actuated causing the mechanism to assume its other position to make the other track continuous, and interacting means between the controlling means holding either of them in its actuated position and releasable by the other when actuated.

10. In a system of the character described, two intersecting tracks and an intersection mechanism adapted to make either track continuous at the intersection, a controlling system for the mechanism embodying a pair of controlling means actuatable by cars or trains on opposite sides of the intersection, said controlling means when both in unactuated position causing the mechanism to assume a certain normal position making one of the tracks continuous, either of said controlling means when actuated causing the mechanism to assume its other position to make the other track continuous, interacting means between the controlling means holding either of them in its actuated position and releasable by the other when actuated, and time period mechanisms operable at times causing the actuation of the other controlling means after the one first mentioned controlling means has been actuated.

11. In a control system for intersection mechanisms, in combination with intersecting tracks and an intersection mechanism

adapted to make either track continuous at the intersection, means actuatable by a car or train approaching the intersection to actuate the intersection mechanism, means actuatable by the car or train leaving the intersection to re-actuate the intersection mechanism, and a time period mechanism operable at times to cause re-actuation after the first actuation.

12. In combination with two intersecting tracks and an intersection mechanism adapted to make either track continuous at the intersection, means actuatable by a car or train approaching the intersection on one track to operate the mechanism to make that track continuous, said means in its normal position causing the intersection mechanism to make the other track continuous, and time period mechanism operable at times to return said means to its normal position after actuation by a car or train.

13. In combination with a track intersection mechanism and control means therefor, said means and mechanism having a certain normal position, time period mechanism operable at times for causing return of the control means and intersection mechanism to normal position within a certain time period after operation of the control means has ceased.

14. In combination with two intersecting tracks and an intersection mechanism adapted to make either track continuous at the intersection, actuating means for the intersection mechanism embodying two controlling means each having a normal position to which they normally automatically return after operation, the two controlling means when in normal position together causing the intersection mechanism to take a normal position in which one track is continuous, and either of the controlling means in abnormal position causing the intersection mechanism to take a position in which the other track is continuous, said two controlling means being actuatable one by a car or train at one side of the intersection and the other by a car or train at another side of the intersection, releasable means for holding each controlling means in abnormal position, and means by which the movement of either of said controlling means to abnormal position causes the release of the holding means for the other said controlling means.

15. In combination with two intersecting tracks and an intersection mechanism adapted to make either track continuous at the intersection, a controlling system for the mechanism embodying a pair of controlling means actuatable by cars or trains on the tracks, one of said controlling means when actuated controlling the intersection mechanism, and interacting means between the controlling means holding one of them in

actuated position and releasable by the other.

16. In combination with two intersecting tracks and an intersection mechanism adapted to make either track continuous at the intersection, a controlling system for the mechanism embodying a pair of controlling means actuatable by cars or trains on the tracks, either of said controlling means when actuated causing the intersection mechanism to move from one of its positions to its other position and be held in the last mentioned position, and both of said means when in normal position cause by their joint action the return of the mechanism to its first mentioned position, and interacting means between the controlling means holding one of them in actuated position and releasable by the other.
17. In combination with two intersecting tracks and an intersection mechanism adapted to make either track continuous at the intersection, a controlling system for the mechanism embodying a pair of controlling means actuatable by cars or trains on the tracks, either of said controlling means when actuated causing the intersection mechanism to move from one of its positions to its other position and be held in the last mentioned position, and both of said means when in normal position cause by their joint action the return of the mechanism to its first mentioned position, and interacting means between the controlling means holding either of them which happens to be first actuated in its actuated position and releasable by the other when actuated.

18. In combination with two intersecting tracks and an intersection mechanism adapted to make either track continuous at the intersection, a controlling system for the mechanism adapted normally to cause the mechanism to be set for making one track continuous and embodying a pair of controlling means actuatable by cars or trains on the tracks, one of said controlling means when actuated being adapted to cause the mechanism to be set in position making the other track continuous, and interacting means between the controlling means holding one of them in actuated position and releasable by the other.

19. In combination with two intersecting tracks and an intersection mechanism adapted to make either track continuous at the intersection, a controlling system for the mechanism embodying a pair of controlling means actuatable one by a car or train approaching the intersection on one of the tracks and the other by the car or train leaving the intersection on the same track, said means having each a normal position in which by their combined action they allow the intersection mechanism to make the other track continuous at the intersection

and each of said means independently of the other adapted in its actuated position for causing the intersection mechanism to make the first mentioned track continuous at the intersection.

20. In a control system for intersection mechanisms, in combination with intersecting tracks and an intersection mechanism adapted to make either track continuous at the intersection, control means actuatable to cause operation of the intersection mechanism to make one track continuous at the intersection, and a time period mechanism operable at times to cause re-operation of the intersection mechanism after the first operation.

21. In a control system for intersection mechanisms, in combination with intersecting tracks and an intersection mechanism adapted to make either track continuous at the intersection, control means actuatable to cause operation of the intersection mechanism to make one track continuous at the intersection, and a time period mechanism operable at times to cause re-operation of the intersection mechanism at the lapse of a predetermined time period after actuation of the control means has ceased.

22. In a control system for intersection mechanisms, in combination with intersecting tracks and an intersection mechanism adapted to make either track continuous at the intersection, control means actuatable to cause operation of the intersection mechanism to make one track continuous at the intersection, means to hold the control means in its actuated condition, and a time period mechanism operable at times to cause release of the holding means.

23. In a control system for intersection mechanisms, in combination with intersecting tracks and an intersection mechanism adapted to make either track continuous at the intersection, control means actuatable to cause operation of the intersection mechanism to make one track continuous at the intersection, means for preventing the actuation of the control means, and a time period mechanism operable at times acting to cause release of the control means from the action of the preventing means.

24. In a control system for intersection mechanisms, in combination with intersecting tracks and an intersection mechanism adapted to make either track continuous at the intersection, means actuatable by a car or train approaching the intersection to actuate the intersection mechanism, means actuatable by the car or train leaving the intersection to re-actuate the intersection mechanism, a time period mechanism operable at times to cause re-actuation after the first actuation; means actuatable by a car approaching on the other track to prevent actuation of the intersection mechanism, and

another time period mechanism operable at times and adapted to nullify the preventing action of said last mentioned means.

25. In combination with intersecting tracks 5 and an intersection mechanism adapted to make either track continuous at the intersection, operating means for the intersection mechanism adapted to move it from one position to the other and adapted when once 10 initially actuated to go through with its operation automatically to move the intersection mechanism from a position making one track continuous to a position making the other track continuous, control means to 15 cause initial actuation of the operating means, and means for preventing initial actuation of the operating means by the control means.

26. In combination with intersecting tracks 20 and an intersection mechanism adapted to make either track continuous at the intersection, operating means for the intersection mechanism adapted to move it from one position to the other and adapted when 25 once initially actuated to go through with its operation automatically to move the intersection mechanism from a position making one track continuous to a position making the other track continuous, control 30 means to cause initial actuation of the operating means, and means for preventing initial actuation of the operating means by the control means; the control means being actuatable by a car or train approaching 35 the intersection on one track and the preventing means being actuatable by a car or train approaching on another track.

27. In combination with intersecting tracks and an intersection mechanism adapted to 40 make either track continuous at the intersection, operating means for the intersection mechanism adapted to move it from one position to the other and adapted when once initially actuated to go through with its operation 45 automatically to move the intersection mechanism from a position making one track continuous to a position making the other track continuous, control means to cause initial actuation of the operating means, the control means having a normal 50 position in which it causes the intersection mechanism normally to stand in a position to make one track continuous at the intersection, and the control means being actuatable 55 by a car or train approaching on another track to cause the intersection mechanism to be moved to position to make that track continuous at the intersection; and

means actuatable by a car or train approaching on the first mentioned track for preventing initial actuation of the operating means by the control means. 60

28. In combination with intersecting tracks and an intersection mechanism adapted to make either track continuous at the intersection, operating means for the intersection mechanism adapted to move it from one position to the other and adapted when once initially actuated to go through with its operation automatically to move the intersection mechanism from a position making one track continuous to a position making the other track continuous, control means to cause initial actuation of the operating means, the control means having a normal 70 position in which it causes the intersection mechanism normally to stand in a position to make one track continuous at the intersection, and the control means being actuatable by a car or train approaching on another track to cause the intersection mechanism to be moved to position to make that track continuous at the intersection; and means actuatable by a car or train approaching on the first mentioned track for preventing initial actuation of the operating means by the control means; said last mentioned preventive means being independent of and having no control over the return of the intersection mechanism to normal position. 75

29. In combination with intersecting tracks and an intersection mechanism adapted to make either track continuous at the intersection, operating means whereby the mechanism is caused to be set in position to make one track continuous at the intersection, and a preventive controlling system to prevent such operation of the intersection mechanism actuatable by a car on the other track 100 and including two control means either of which when actuated causes prevention of such said operation, said control means being actuatable one by a car or train approaching the crossing on said track and 105 the other by a car or train moving away from said crossing on said track; and interacting means between the control means holding the first mentioned one in actuated position and releasable by the other. 110

In witness that I claim the foregoing I have hereunto subscribed my name this 28th day of December 1917.

SAMUEL E. McFARLAND.
